LOCK SLIDER FOR SLIDE FASTENERS

Gustaf Dahlin, St. Catharines, Ontario, Canada,
assignor to Lightning Fastener Company, Limited, St. Catharines, Ontario, Canada

Application March 22, 1939, Serial No. 263,557

9 Claims. (Cl. 24—205.5)

My invention relates to improvements in lock sliders for slide fasteners of the type comprising a pair of stringers carrying interdigitating members adapted to be engaged or disengaged by the movement of the slider therealong. The slider is particularly adapted for construction from non-metallic, i. e. plastic, material but it may also serve efficiently for metallic fasteners.

The chief object of the invention is to provide a lock slider construction whereby the locking mechanism is operated by the normal actuation of a pull member which serves to draw the slider along the interdigitating members, and to which the stress produced by actuation of the pull member is taken by an integral part of the slider itself, rather than by the locking mechanism. Such construction also provides a slider which may be readily assembled, difficult assembly having been an objectionable feature of prior devices.

It is also an object to devise a slider which has a minimum number of parts, which is neat in appearance, and which is compact and has the delicate working parts protected to prevent them being rendered inoperative by catching in the material of the object upon which the fastener is used.

With the above and other objects, which will hereinafter become apparent as the specification proceeds, in view, the invention consists of the construction and arrangement all as hereinafter more particularly described and illustrated with reference to the accompanying drawing, in which:

35 Fig. 1 is a plan view of my improved slider showing a fragmentary section of a fastener;

Fig. 2 is a longitudinal sectional view thereof, on an enlarged scale, taken along the line 2—2 of Fig. 1, and showing the slider in the locked position;

40 Fig. 3 is a view corresponding to Fig. 2 but showing the slider in the unlocked position;

Fig. 4 is a transverse sectional view of the slider taken along the line 4—4 of Fig. 1;

45 Fig. 5 is a perspective view of the slider body without the track;

Fig. 6 is an inverted perspective view of the track thereof; and

Fig. 7 is a longitudinal sectional view of an 50 alternative form of the slider showing the slider in the locked position corresponding to Fig. 2.

Like characters of reference designate corresponding parts in the different views.

Referring to the drawing, the conventional slide fastener with which my invention is concerned

comprises a pair of flexible stringers 1 and 2 provided with the interdigitating elements 3 adapted to be engaged and disengaged by a slider. The latter, broadly, consists of a body having upper and lower wings 4 and 5 which, with the diamond 6, define channels for the guidance of the interdigitating members 3.

According to my invention, I provide on the upper wing 4 of the slider a pair of lugs 7 and 8 which may well be moulded integrally with the rest of the slider when the latter is made of a plastic material. The lugs 7 and 8 are provided with undercut portions forming projections 9 and 10 on the lugs which are adapted to engage shoulders 11 and 12 on a hollow track member 13, by which an orthodox pull, such as the ring 14, is retained on the slider. The lugs 7 and 8 are provided with ears 15 and 16, respectively, under which the ring 14 is caught when it is positioned for opening and closing, respectively, of the fastener, in which positions, it will be noted, the lugs 7 and 8, respectively, take the whole force transmitted to the slider by the ring 14.

Along the sides of the lug 7 are provided slots 17 and 18 in the wing 4 in which are received locking projections 19 and 20, respectively, of the track 13. A spring element 21, which may well be a piece of spring wire having one flattened extremity 22, is secured to the lug 10 with the flattened portion embedded therein and with its free extremity lying in a slot 23 in the lug 7 and overlying the shoulder 11 of the track.

As shown best in Fig. 2, the spring 21 normally holds the track 13 against the wing 4 of the slider with the locking projections 19 and 20 protruding through the slots in the wing into engagement with the fastener elements 3 for locking of the slider. On grasping the pull ring 14 to operate the slider, the track 13 is lifted, pivoting about the projection 18 on the lug 8 until the ring engages the ear 15 on the lug 7, by which time the locking projections 19 and 20 have been withdrawn clear of the fastener elements 3 to permit the slider to slide therealong. On release of the pull 14 the spring 21 causes the locking projections to again engage the fastener elements for locking of the slider. It will be noted that the projections 19 and 20 are staggered longitudinally of the track, whereby each projection engages an interlocking element 3 of the respective stringers to provide increased locking action and longer life for the locking means.

In order to decrease the height of the track 13, the wing 4 may be given a concavity 24 which accommodates the curved portion of the ring 14.

when it is positioned at an angle with the wing of the slider.

It is an important feature of the invention that the locking system may be readily assembled. In 5 the form of the slider described above, the spring element may be readily installed in the lug 8 as shown in Fig. 5, whereafter, to complete assembly of the slider, it is merely necessary to insert the locking projections of the track in the slots 10 17 and 18, catch the shoulder 11 under the free extremity of the spring 21 and then swing the track down into position with the shoulder 12 snapping over the projection 10 which leaves the slider in its completely assembled form.

15 According to an alternative construction, as illustrated in Fig. 7, the shoulder 12 and the projection 10 on the lug 8 may be dispensed with and the pivoting end of the track 25 may be located on the slider, when placed in position 20 over the lugs 7 and 8, by inserting the spring 26 through an orifice 27 in the track and pressing the spring home to a position corresponding with that of the spring 21 in the first described embodiment. The projection of the spring 26 25 beyond the lug 8 serves as an anchor for the track about which the track may rock. Such a construction operates similarly to that previously described and is also very simple to assemble.

By virtue of the construction of the improved 30 slider, it may be very readily assembled without the necessity of complicated operations on very small parts and is hence economical to manufacture. Since substantially all the working parts are enclosed within the hollow track, they 35 are protected against accidental disarrangement and the slider also has a very neat appearance. The construction whereby the fastener opening or closing force is taken by the lugs on the slider, rather than by track, also enables the track to 40 be made of plastic material without its strength being objectionably low, and permits the bulk of the track to be reduced over that necessary in orthodox constructions.

While I have shown and described in this application two embodiments which my invention 45 may assume in practice, it will be understood that these embodiments are merely for purposes of illustration and description and that various other forms may be devised within the scope of 50 my invention as defined in the appended claims.

What I claim as my invention is:

1. A lock slider for a slide fastener comprising a body channelled for the passage of the fastener elements, a pair of track mounting lugs 55 on the body, an elongated spring member secured at one extremity in one lug, a hollow track housing the lug and the spring member, a pivot for the track on said one lug, a shoulder disposed within the track adjacent the other lug, 60 a locking projection on the track passing through an orifice in the body and adapted to be held in locking engagement with the fastener elements by pressure of the free extremity of the spring on the shoulder, a pull member carried by the 65 track for rocking the track about the pivot for lifting the locking projection out of engagement with the fastener elements, means for limiting the rocking movement of the track, and an ear on at least one of said lugs for directly engaging 70 the pull member when the locking projection is disengaged from the fastener elements.

2. A lock slider for a slide fastener as claimed in claim 1 wherein the pivot for the track comprises a projection on the lug and a shoulder 75 on the track engageable therewith.

3. A lock slider for a slide fastener as claimed in claim 1 wherein the pivot for the track comprises an extension of the elongated spring member received in an orifice in the extremity of the track. 5

4. A lock slider for a slide fastener comprising a body channelled for the passage of the fastener elements, a pair of upstanding lugs on the slider body spaced apart longitudinally of the body, a spring member secured at one end in one of the 10 lugs and passing freely through a slot in the other lug, a hollow track in which the lugs and the spring member are received, a shoulder on one end of the track engaged by the free extremity of the spring member which passes 15 through the slotted lug, means on the track and the other lug for rockably retaining the track thereon, a locking projection on the track adjacent the slotted lug and passing through an orifice in the body and adapted to be held in 20 locking engagement with the fastener elements by the pressure of the spring on the track shoulder, a pull member carried by said track between the lugs for rocking the track about the lug to 25 which the spring member is secured for lifting the locking projection of the track out of engagement with the fastener elements, a projection on the slotted lug engageable with the shoulder on the track for limiting the lifting movement of the track, and an inwardly directed 30 ear on each lug for directly engaging the pull member when the locking projection is disengaged from the fastener elements.

5. A lock slider for a slide fastener as claimed in claim 4 wherein the means for retaining the track on said unslotted lug comprises a second shoulder on the track and a projection on the unslotted lug. 35

6. A lock slider for a slide fastener as claimed in claim 4 wherein the means for retaining the track on said unslotted lug comprises an extension of the spring member beyond the unslotted lug received in an orifice in the track. 40

7. A lock slider for a slide fastener comprising a body channelled for the passage of the fastener elements, a pair of upstanding integral lugs thereon located in spaced relation longitudinally of the body, an inwardly directed ear on each lug, a spring strip secured at one extremity in one of the lugs and lying substantially 45 parallel to the body and projecting freely through a slot in the other lug, a hollow track of temporarily deformable material housing the lugs and spring, a pull member engaging the track 50 between the lugs, a pair of locking projections on the track each adapted to engage one of the elements of the respective series of interlocking elements of the fastener and projecting through a pair of orifices in the slider body disposed one 55 on either side of the slotted lug, a shoulder on each extremity of the track and located therewithin, a projection on the unslotted lug adapted to engage one track shoulder to serve as a fulcrum for the track, and a projection on the 60 slotted lug located over and spaced from the free extremity of the spring strip, the track being adapted to be installed on the lugs by hooking the shoulder adjacent the locking projections under the free extremity of the wire spring and 65 snapping the other shoulder over the unslotted lug, the projection on the slotted lug serving to limit the motion of the track when the latter is lifted by means of the pull member against the reaction of the wire spring, and the lug ears 70

75

serving as the sole means for transmitting force from the pull member to the slider.

8. In a lock slider for a slide fastener, a body channelled for the passage of the fastener elements, track mounting means thereon, a projection on each extremity of such means, a hollow track housing the mounting means, a shoulder disposed inwardly of each extremity of the track and engageable with said projections for rockably retaining the track on the body, a locking projection on the track, and an elongated spring member underlying the track and having one extremity secured in the track mounting means and its free extremity in engagement with one

of said track shoulders for normally retaining the locking projection in operative position.

9. In a lock slider for a slide fastener which includes a body channelled for the passage of the fastener elements, a pair of lugs on the body, a hollow track rockably mounted on said lugs, a pull member slidably carried on said track between the track and said body, fastener element locking means on the track, and an ear on at least one of said lugs engageable directly with the pull member for transmitting the full slider moving force from the pull member to the slider body. 5 10

GUSTAF DAHLIN.
